his Attorney.

UNITED STATES PATENT OFFICE.

HENRY H. BRUNINGS, OF BROOKLYN, NEW YORK, ASSIGNOR TO AMERICAN LITHOGRAPHIC COMPANY, OF NEW YORK, N. Y., A CORPORATION OF NEW YORK.

MEANS FOR MAKING ETCHED PRINTING PLATES.

Application filed October 21, 1925. Serial No. 64,045.

This invention relates to means for making etched printing plates and has for its object to provide means, simple in character and accurate in result. Other objects will 5 appear later herein.

While my improvements are applicable to the production of printing plates of various characters, they are particularly useful in the production of intaglio plates, including 10 cylinders, for gravure printing, and in the accompanying drawing is shown the preferred form of my improved apparatus.

Therein, Figure 1 represents a photographic print, preferably a positive print, 15 on a transparent base. Fig. 2 is a plan view of a device for composing a plurality of prints, such as shown in Fig. 1, in predetermined relation. Fig. 3 is an end elevation corresponding with the showing of Fig. 2. 20 Fig. 4 is an enlarged plan view of a detail of what is shown in Figs. 2 and 3.

From an original object, drawing or painting, one or more photographic negatives are made; one, if the object or drawing is to be 25 printed in one color only, several if the printing is to be done in several photographically separated colors. First, as to one color. From a negative of known character, a positive print is made in the well 30 known manner, by contact with a light sensitive film on celluloid, or preferably glass. This positive is developed and fixed and provided with the usual opposite pair of cross gage lines 2, 3, Fig. 1. Then this film 35 image of Fig. 1, with duplicates thereof, or others of its kind, such as 7, 8 and 9, Fig. 2, sufficient to suitably fill a desired area of plate, are arranged in approximate positions on a transparent base, such as a glass plate 4, 40 which may be laid upon a cross ruled composing table, or preferably upon the cross ruled table 5 of the composing machine of Fig. 2. Then, one by one the film images are accurately located on plate 4 of table 5, 45 preferably by means mounted on said table and which means will be described in detail later herein. As each film image or transparent positive is accurately located on said plate, it is fixed thereto by some convenient 50 means, such as a transparent adhesive.

By means of the composing device of Fig. 2, a succession of plates, as 4, may have assembled thereon, respectively, a series of sets of transparent positives in exactly the 55 same relative positions as in the first assem-

bled set. These sets may be duplicates of the first set if desired or, if a series of color value positives are being prepared, the positives of the successive sets may represent successive color values. But in any case each 60 set will register with all the other sets of the series.

Reverting now to the device of Figs. 2, 3 and 4, for accurately composing the photographic prints, as 6, of Fig. 1, on base 4. 65 Table 5 is provided with a suitable carriage guiding means, as rail 10, near one edge thereof, as 11, and thereon is mounted for traverse, carriage 12, having arm 13 extending across table 5 at right angles to rail 10. Said arm may be provided with roll 36 pivoted at its outer end, for traverse on table 5, for supporting said arm. Carriage 12 is provided with foot 14 reaching downwardly to table 5 and having gage mark 15 70 thereon for accurate reading against scale 16 on said table, parallel with rail 10. Said table is also provided with a similar scale 17, at right angles to scale 16, across end 18 of table 5. The graduations of said scales 80 may be projected across the table in either direction to serve as approximate locating means for the prints which are being arranged. For fine adjustment of carriage 12 on rail 10, clamp block 19 straddles rail 10 85 and may be releasably secured thereto by clamp screw 20. Mounted for rotation in ear 21 of block 19, but secured against end-wise movement therein, is screw 22 in threaded engagement with ear 23 of carriage 90 12.

Mounted for traverse at right angles to rail 10, on arm 13, is slide 24. Said slide is provided with means for fine adjustment similar to that just described in connection 95 with carriage 12, as clamp block 25 and screw 26. Said slide has arm 27 extending therefrom transversely to arm 13, and mounted for vertical movement therein is plunger 28. Said plunger is preferably provided with hand actuated means for vertical movement, such as rack teeth 29 in engagement with gear 30 fixed to stem 31 pivotally mounted in arm 27. Said stem 31 may be rotated by thumb button 32 fixed thereto. 100 Plunger 28 has foot 33 extending preferably to the left therefrom and the outer end of said foot has narrow cross slots 34, 35 therein, through which the gage lines, as 2, 3 of print 6, may be read. Said plunger is ar- 110

ranged for vertical movement, so as to bring foot 33 into close contact with the print gage lines for accuracy of reading, and at other times to back said foot away to allow 5 free removal of plate 4.

While one cross traverse slide, as 24, is sufficient for the carrying out of those steps in my improved method for which the device of Figs. 2, 3 and 4 is provided, facility 10 of operation is enhanced by the provision of a second slide 37, equipped in all respects as is slide 24 but preferably slides 24, 37 are right and left duplicates, their arms 27 and 38, respectively, facing inwardly toward 15 each other so that plunger feet 33, 39 may be brought near together to accommodate small prints, as 7, 8.

The operation of the device of Figs. 2, 3 and 4 is as follows: For convenience of illustration 20 the several prints 6, 7, 8 and 9 on transparent bases are shown of different sizes, but they may as well be of one size if desired. They are first laid in approximate positions, suitably spaced in accordance with 25 the ultimate use to which they are to be put. For instance, print 6 is placed on plate 4 with its gage lines 2, 3 in approximate coincidence with line 11½ of scale 16 and with lines 2½ and 11½ of scale 17. Then cross 30 slot 34 in plunger foot 33 is brought into accurate coincidence with line 2½ and the corresponding cross slot of plunger foot 39 is brought into accurate coincidence with line 11½, of scale 17, by moving slides 24, 35 37 to approximate positions and then to accurate positions by means of their adjusting screws, respectively. Then carriage 12 is moved toward edge 18 of table 5 a sufficient 40 distance to bring gage mark 15 of foot 14 thereof into approximate coincidence with line 11½ of scale 16 and is accurately located by means of adjusting screw 22. Then by 45 carefully shifting print 6 on plate 4, cross lines 2 and 3 are brought to read with the cross slots in feet 33, 39, respectively, and 50 said print is fixed in position on said plate by an adhesive or some other known convenient means. Then the other prints, as 7, 8, 9, are similarly located and fixed on plate 4.

A record is then made of the several gag- 55 ing points employed and plate 4 is removed, to be replaced by a similar plate, on which a similar set of prints may be similarly ar- 60 ranged in accurate register with the prints on plate 4, by reference to the record of gag- 65 ing points.

If only one slide, as 24, is used on arm 13, its cross slot 34 of foot 33, must first be 60 set for locating gage line 2 on scale line 2½ of scale 17 and after said gage line 2 is located, said arm 13 is shifted to bring its cross slot 34 into register with scale line 11½ of scale 17 and gage line 3 is then set thereto.

65 In view of the known character of the

later steps in my improved method it has not been considered necessary to illustrate them in the drawing. Those skilled in the art will readily understand all the details from the description herein.

The term gelatin as herein used will be understood to include any suitable light sensitive material.

I claim:

1. A composing device including in combination a table having carriage guiding means near one edge thereof, a carriage mounted for traverse on said guiding means, there being a scale on said table parallel with said carriage guiding means, means on said carriage for reading against said scale, an arm fixed to said carriage and extending over said table at right angles to said guiding means, a slide mounted for traverse lengthwise said arm, said table being also provided with a transverse scale at right angles to said first mentioned scale, and means on said slide for reading against said transverse scale.

2. A composing device including in combination a table having carriage guiding means near one edge thereof, a carriage mounted for traverse on said guiding means, means releasably fixed to said guiding means and in operative relation with said carriage for minutely adjusting the position of said carriage, there being a scale on said table parallel with said carriage guiding means, means on said carriage for reading against said scale, an arm fixed to said carriage and extending over said table at right angles to said guiding means, a slide mounted for traverse lengthwise said arm, said table being also provided with a transverse scale at right angles to said first mentioned scale, means on said slide for reading against said transverse scale, and means releasably fixed to said arm and in operative relation with said slide for minutely adjusting said slide.

3. A composing device including in combination a table having carriage guiding means near one edge thereof, a carriage mounted for traverse on said guiding means, means releasably fixed to said guiding means and in operative relation with said carriage for minutely adjusting the position of said carriage, there being a scale on said table parallel with said carriage guiding means, means on said carriage for reading against said scale, an arm fixed to said carriage and extending over said table at right angles to said guiding means, a slide mounted for traverse lengthwise said arm, said table being also provided with a transverse scale at right angles to said first mentioned scale, means on said slide for reading against said transverse scale, said reading means comprising a vertically adjustable plunger having a foot with cross slots therein, and means releasably fixed to said arm and in operative

relation with said slide for minutely adjusting said slide.

4. A composing device including in combination a table having carriage guiding means near one edge thereof, a carriage mounted for traverse on said guiding means, and in operative relation with said carriage for minutely adjusting the position of said carriage, there being a scale on said table parallel with said carriage guiding means, means on said carriage for reading against said scale, an arm fixed to said carriage and extending over said table at right angles to said guiding means, two slides mounted for traverse lengthwise said arm, said table being also provided with a transverse scale at right angles to said first mentioned scale, means on each of said slides for reading against said transverse scale, and two clamp blocks releasably fixed to said arm and in operative relation with said slides for minutely adjusting said slides, respectively.

5. A composing device including in combination a table having carriage guiding

means near one edge thereof, a carriage mounted for traverse on said guiding means, means releasably fixed to said guiding means and in operative relation with said carriage for minutely adjusting the position of said carriage, there being a scale on said table parallel with said carriage guiding means, means on said carriage for reading against said scale, an arm fixed to said carriage and extending over said table at right angles to said guiding means, two slides mounted for traverse lengthwise said arm, said table being also provided with a transverse scale at right angles to said first mentioned scale, means on each of said slides for reading against said transverse scale, said reading means comprising vertically adjustable plungers having feet with cross slots therein, respectively, and two clamp blocks releasably fixed to said arm and in operative relation with said slides for minutely adjusting said slides, respectively.

In witness whereof, I hereby affix my signature this 19 day of October, 1925.

HENRY H. BRUNINGS.
